UNITED STATES PATENT OFFICE.

JOSEPH R. SMITH, OF WATERBURY, CONNECTICUT, ASSIGNOR TO THE WATERBURY BUTTON COMPANY, OF SAME PLACE.

DESIGN FOR BUCKLE.

Specification forming part of Design No. 7,005, dated December 2, 1873; application filed October 11, 1873.
[Term of Patent 7 years]

To all whom it may concern:

Be it known that I, JOSEPH R. SMITH, of Waterbury, in the county of New Haven and State of Connecticut, have invented a new Design for Buckle; and I do hereby declare the following, when taken in connection with the accompanying drawing and the letters of reference marked thereon, to be a full, clear, and exact description of the same, and which said drawing constitutes part of this specification, and represents a front view.

This invention relates to a design for belt-buckle; and consists in the configuration and ornamentation, as shown in the accompanying illustration, and as hereinafter described.

The buckle is of elliptical form, with a narrow edge surrounding it. On the center is a medallion of a female head, in outline corresponding to the form of the plate, and between the medallion and the edge is a plain surface.

I claim as my invention—

The design for buckle, as herein described and shown in the accompanying illustration.

Witnesses: JOSEPH R. SMITH.
